G. B. PETSCHE,
ADMISSION VALVE FOR GAS ENGINES.
APPLICATION FILED MAR. 7, 1906.

901,256.

Patented Oct. 13, 1908.

UNITED STATES PATENT OFFICE.

GUSTAV B. PETSCHE, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

ADMISSION-VALVE FOR GAS-ENGINES.

No. 901,256.

Specification of Letters Patent.

Patented Oct. 13, 1908.

Original application filed December 30, 1904, Serial No. 238,917. Divided and this application filed March 7, 1906.
Serial No. 304,627.

To all whom it may concern:

Be it known that I, GUSTAV B. PETSCHE, a subject of the Emperor of Germany, residing in the city and county of Philadelphia, in the State of Pennsylvania, have invented a certain new and useful Improvement in Admission-Valves for Gas-Engines, of which the following is a true and exact description, reference being had to the accompanying drawings, which form a part thereof.

My invention relates to the construction and operation of admission valves for gas engines, and has for its object to provide an admission valve of simple construction and by which the same mixture proportionally of air and gas is secured for all adjustments of the valve.

The nature of my improvements will be best understood as described in connection with the drawings in which they are illustrated and in which

Figure 1, is an elevation of a portion of an engine equipped with my valve and valve actuating devices. Fig. 2, is a perspective view of the valve actuating mechanism, and Fig. 3, a vertical central section through a valve and the parts immediately connected therewith.

A, indicates the bed plate of the engine, A', the housing for the main shaft, A², the frame of the engine.

B, indicates the gas engine cylinder abutting against the frame, B², B², standards arranged at each end of the cylinder B³, B³, brackets secured to the side of the cylinder.

B⁴, is the piston rod.

K, K, are the admission valve casings, P, P, the exhaust valve casings.

E, E, are slide guides secured on the brackets B³, and formed with two parallel guideways, and also with brackets supporting pivot pins E⁴, on which pivot pins are pivoted levers indicated at F', F², and G', G², those marked F', F², being connected to actuate the admission valves, and those marked G', G², being connected to actuate the exhaust valves.

I', I², are cam blocks sliding in the guideways E, and secured to rods H', H², which, through rods H⁵, H⁶, are connected to rock levers H⁶, H⁷, said levers being in turn connected by rods H⁸, H⁹, with cams H¹⁰, and

H¹¹, secured on a shaft H¹², which is actuated through gear wheels H¹³, H¹⁴, shaft 55 H¹⁵, and gears H¹⁶, H¹⁷, by the main shaft H¹⁸, the eccentrics H¹⁰, H¹¹, being set at 90° apart, and the shaft H¹², being driven at one-half the speed of the main shaft. The rock levers G', G², connect through rods R, 60 with the exhaust valves Q, Q', the part Q', being a cylindrical guide moving in the guideway P³, of the exhaust casing P, and the valve proper indicated at Q, fitting on a removable seat P⁴. The special construction 65 of this exhaust valve forms the subject matter of my application for Letters Patent, filed March 7th, 1906, Serial Number 304,626.

The rock levers F', F², connect through rods N², with angle heads N', which may be 70 turned in either direction with rock levers N, pivoted on the top of the standards B², and connected at their other ends with the valve rods M, to the bottom of which rods are secured the valves M', each of which is 75 adapted to seat itself on its seat K', at the bottom of the inlet casing.

Before going further with the description of the admission valve construction, I would state that the rock levers actuating the admission and exhaust valves are arranged alternately; that is to say, if the first admission valve lever is actuated by a cam secured to the rod H', the next one will be arranged to be actuated by a cam secured to the rod 85 H², and so on, the same alternating arrangement being also applied to the actuation of the exhaust valves. The valve actuating mechanism briefly described above forms the subject matter of my application for Letters 90 Patent No. 238,917, filed December 30, 1904.

To return now to the mechanism of the admission valve, it will be seen that the valve casing K, is formed with an air chamber K', and a gas chamber K², and has fitting into 95 it a seat portion K³, provided with seats as indicated at K⁴, and K⁵. A separate portion K', at the bottom of the casing K, fits into the admission valve opening of the cylinder, and is formed with the seat K⁷, for the 100 valve M'.

K⁸, indicates the cover of the casing through which the sleeved valve stem L, having secured to it the mixture controlling valve having the valve portions, one indicated at L', and adapted to seat itself on the 105

seat K³, and the other indicated at L², made in the form of a cylinder valve and adapted to close the port indicated at K⁴. Through the sleeved stem L, extends the valve rod M.

5 The stem M, as already stated, is secured to one end of the lever N, on which lever is secured a grooved segment N².

O, is a lever arm, one being coupled to the top of each sleeved stem L, the levers being 10 pivoted on shafts O', having squared ends movable in guide slots B⁶, formed in the standards B². The levers O, are connected by links O², with slides O³, moving in the slotted segments N³, the links being connected 15 through rods O⁴, and lever arms O⁵, with a longitudinal running shaft O⁶, supported in the standards B², and coupled, through arms and links indicated at O⁷, to be actuated by a governor O⁸.

20 It will be seen that the valves M', being directly connected through the mechanism described with the valve actuating levers which are actuated by the sliding cams, will always move in a fixed relationship to the 25 motion of the actuating eccentric, and it will also be seen that when the parts are in the position shown in Fig. 3, that is to say, when the slide O³, stands directly above the connection of the link O², with the link O, the 30 sleeved stem L, and the valves L', L², will move positively and in fixed relationship to the motions of the valve M', all the valves opening and closing simultaneously.

The regulation of the admission in this 35 construction of valve is accomplished through the action of the governor which, by turning the shaft O⁶, shifts through the lever O⁵, and link O⁴, the position of the slide O³, the movement of the slide toward the right 40 necessarily effecting through the connections with the sleeved stem L, the relative opening and closing of the valve L', and L², with reference to the movement of the valve M'; but irrespective of the cut-off, it is obvious 45 that this construction of valve admits always

a similarly proportioned mixture of air and gas to the cylinder with the advantages which are well recognized as incident to an even and constant gas mixture.

Having now described my invention, what 50 I claim as new and desire to secure by Letters Patent is:

1. In a gas engine, an inlet valve M', and means operating to open and close said valve in fixed and positive relation to the movements of the engine, in combination with throttle valves acting on the air and gas ports, an adjustable connection from the means actuating valve M', to the throttle valves for opening and closing the same, and 55 means actuated by the governor of the engine and acting to adjust said connection to vary the motion of the throttle valves with reference to valve M'.

2. In a gas engine, an inlet valve M', having a stem M, and means for actuating the valve through said stem in fixed relation to the movements of the engine, in combination with a sleeve stem L, movable on stem M, and positively coupled to the actuating mechanism of said stem by adjustable connections, means actuated by the engine governor for shifting said adjustable connections, and 70 throttle valves for the air and gas supply, connected to stem L, as specified.

3. In a gas engine, an inlet valve, a pivoted operating lever for the valve, means for turning said lever about its fulcrum in definite relation to the movements of the engine to open and close said inlet valve, a 80 mixture controlling valve, a governor, and means controlled by the governor for positively coupling said mixing valve to said lever at varying distances from the lever fulcrum in response to variations in the speed 85 of the engine.

'GUSTAV B. PETSCHE.
